UNITED STATES PATENT OFFICE.

O. FREDERICK OGREN, OF CHICAGO, ILLINOIS.

PROCESS OF DECORATING GLASS.

Application filed October 1, 1924. Serial No. 741,068.

To all whom it may concern:

Be it known that I. O. FREDERICK OGREN, a subject of the King of Sweden, residing at Chicago, in the county of Cook and State of

Illinois, have invented new and useful Improvements in Processes of Decorating Glass, of which the following is a specification.

This invention relates to a process of decorating plate glass, mirrors, panels or any sheet glass used for ornamental purposes and the invention also relates to the product of such process.

Briefly stated, an important object is to provide simple means by which a plurality of colors may be economically and effectively employed to reproduce floral and other designs on a piece of glass.

A further aim of the invention is to provide means whereby the necessity of deeply grooving the rear side of the glass in the engraving, cutting, etching or similar operation preparatory to the application of the color matter is overcome.

Also, an important aim is to greatly simplify and cheapen the engraving or other cutting operation on the glass by leaving the walls of the grooves unpolished and completing the process of decorating the glass without causing the unpolished walls of the grooves to minimize the effectiveness of the decoration.

A further object is to provide means to decorate glass in such a manner that an extremely durable and attractive product is produced.

Other objects and advantages will be apparent during the course of the following description.

In the accompanying drawing forming a part of this application and in which like numerals are employed to designate like parts throughout the same,

Figure 1 is a front elevation of a glass constructed in accordance with this invention;

Figure 2 is a rear elevation illustrating the bronze powder mixed with a bronzing liquid applied to the rear side of the glass to fill some or all of the grooves or depressions therein;

Figure 3 is a detail sectional view through the glass.

In the drawing wherein for the purpose of illustration is shown a preferred embodiment of the invention, the numeral 5 design-

nates a piece of glass of any shape or style and having its rear side cut by engraving, etching or otherwise to form one or more depressions 6.

After grooving the rear surface of the glass in any well known manner it is cleaned and thoroughly dried. When this has been done a coating of bronze powder mixed with a bronzing liquid is applied with a brush 65 over the entire design if only one color is employed.

If a combination of colors is desired the different colors are applied to each different part of the design. When dry, a sharp 70 knife is employed to scrape off the coloring matter which may have run over on the flat rear surface of the glass.

It will be seen that the walls of the grooves of the design are now coated with 75 one or more colors and preparatory to silvering or applying a contrasting color of bronze powder mixture or any other kind of paint or pigment color, the rear surface of the glass is again cleaned.

Considering the invention as thus far described it will be seen that the rear side of the glass is grooved in any suitable manner after which the several grooves are provided with coloring matter and the surplus coloring matter is scraped off. A silvering or contrasting coloring is now applied to the entire rear surface of the glass and allowed to remain.

Finally a protective or backing paint such 90 as that employed in the manufacture of mirrors is applied to the entire rear surface of the glass.

When viewed from the front, the design produced in accordance with this invention 95 will stand out brilliantly against a light reflecting background of silver or any other color desired.

One of the principal advantages of the invention resides in the fact that the bronze 100 powder mixture will adhere to the engraved or sunken part and show the engraving in every detail with the same effect which is produced by silvering. Other paints or pigments will not bring the same effect. They 105 will make a color, but at the same time deaden the effect of the engraving. In scraping off the colors from the surface of the glass the bronze powders will come off smooth and evenly on account of their 110 grainy consistency.

Also, a further advantage over silvering

the design resides in the fact that the bronze powders will give a lustrous finish without the necessity of polishing the design before the application of the coloring matter. The application of silver to the unfinished walls of the grooves of the engraving produces a grey dull finish.

It has also been found that a design produced in accordance with this invention does not require that the grooves in the glass be deep as when silvering is applied. Shallow grooves are sufficient.

A plurality of colors may be employed for producing the desired effect. For instance, a floral design consisting of roses, daisies, leaves and stems by this process appears in natural colors, with the daisies white with yellow centers, the roses red and the leaves and stems green.

A variety of color effects can be produced by this process and be made to match any decorative scheme where delicate color effects are required. It may be used for ornamental mirrors and panels, inlays on furniture, lamp stands, clocks, radio and phonograph cabinets, pianos, picture frames, or wherever a plate or sheet glass panel is desired.

Having thus described the invention, what is claimed is:—

1. The herein described process of decorating glass which consists in forming one side of the glass with grooves and allowing the walls of the grooves to remain unfinished, and subsequently applying a bronze coloring paint directly to the unfinished walls of the grooves.

2. The herein described process of decorating glass which consists in forming one side of the glass with depressions and allowing the walls of the depressions to remain unfinished, subsequently applying a coating of bronzing pigment directly to said unfurnished walls and then applying a reflecting means to the side of the glass with the depressions.

3. The process as outlined in claim 2, the reflecting means being provided with a protective coating.

4. As an article of manufacture, a piece of glass having one side grooved to provide a decorative design, the walls of the groove being unfinished, a coating of bronze powder mixed with a bronzing liquid applied directly to and in intimate contact with the unfinished walls of the grooves, a reflecting coating applied to the grooved side of the piece of glass, and a protective coating applied to the reflecting coating.

5. As an article of manufacture, a piece of glass having one side grooved to provide a decorative design, the walls of the grooves being unfinished, a coating of bronze powder mixed with a bronzing liquid applied directly to and in intimate contact with the unfinished walls of the grooves, a reflecting coating applied to the grooved side of said piece of glass, a protective coating applied to the reflecting coating, the grooves in the glass being shallow.

In testimony whereof I affix my signature.

O. FREDERICK OGREN.
